UNITED STATES PATENT OFFICE.

HALBERT K. HITCHCOCK, OF PITTSBURGH, PENNSYLVANIA.

APPARATUS FOR APPLYING ABRASIVE TO GRINDING APPARATUS.

Application filed January 22, 1924. Serial No. 687,702.

The invention relates to an apparatus for handling, grading, and applying abrasive, such as sand, to grinding apparatus, and particularly to such an apparatus for use in connection with a straight away operation for surfacing sheet glass, marble or the like, in which a series of grinding machines are employed, beneath which the sheets of glass or other material to be surfaced are carried, and the surface gradually reduced to the desired degree of smoothness by the use of finer and finer grades of sand or other abrasive.

The invention has for its principal objects, the provision of an improved apparatus for accomplishing the function as above set forth, wherein the density of the mixture of abrasive and water in the grading tank is automatically maintained constant throughout, as well as the upward velocity of the upward flow through the tank which gives the grading effect, thus insuring that the degree of fineness of the grade at each level and the proportion of abrasive to water shall remain correspondingly constant, and further, the provision of an apparatus of very simple, reliable construction.

Briefly stated, the apparatus, in its preferred form, includes a conical grading tank supplied with a mixture of sand and water at its lower end by means of a motor operated pump, which withdraws the mixture from a sump to which the drainage from the various grinding machines is returned; a motor operated device for feeding sand to the sump; automatic means governed by the density of the mixture in the tank for regulating the feed of the sand; and other automatic means governed by the amount of liquid overflowing from the tank for regulating the speed of operation of the pump. The two automatic controlling means serve to maintain the proportion of water to abrasive constant (which proportion can be made the one to give the highest efficiency in grinding), and to maintain a constant upward velocity in the tank, so that the degree of fineness of the various grades taken from the various levels is maintained constant. The two controlling means are also preferably so correlated that, when the overflow from the tank is stopped entirely as by the stoppage of the pump, the feeding of the sand is automatically stopped. The apparatus as herein set

forth, while constituting the preferred embodiment of the invention, is merely illustrative of such invention in the broad form, as various other arrangements of controlling means might be employed without departing from the invention. Such preferred form of apparatus is shown in the accompanying drawings wherein:

Figure 1 is a vertical section taken through the apparatus. Fig. 1^a is an enlarged detail section. Fig. 2 is a partial plan view of the apparatus. Fig. 3 is a section on the line III—III of Fig. 1. Fig. 4 is a section through a modification. Fig. 5 is a section on the line V—V of Fig. 4. Fig. 6 is a partial end view. And Fig. 7 is a partial side view on an enlarged scale.

Referring first to the general arrangement, the principal parts of the apparatus may be enumerated as follows: 1 is a conical grading tank supplied with a mixture of abrasive and water from the drainage sump 2 of the grinding machines by means of the rotary pump 3, which sump is provided with a suitable overflow passage (not shown); 4, 5, 6, etc. are a series of outlet pipes leading from different levels in the grader for carrying abrasive of different degrees of fineness to the various grinding units; 7 is a variable speed electric motor which drives the pump 3; 9 is a sand hopper supplied from the chute 10, in the bottom of which is a screw 11 for feeding the sand to the sump 2; 12 is a variable speed electric motor for driving the screw 11 through the reducing gearing in the casing 13; 14 is a motor starter for the motor 12 of ordinary commercial type which is stopped and started by means of the push buttons 15 and 16; 17 is a manually operated rheostat for the field of the motor 12; 18 is an automatic device for stopping and starting the motor 12 through the motor starter; 19 is a device controlled by the density of the mixture in the tank 1 for governing the speed of the sand feeding motor 12; 20 is a pressure rheostat lying in the circuit of the field of the motor 12 and controlling the speed thereof, which device is operated by the tube 19; 21 and 22 are bells controlled from the electro-magnetic operating device 23 for indicating the stopping and starting of the motor 12; 24 is an overflow trough; 25 is an overflow pipe; 26 is a receptacle for receiving the overflow

110

mounted so that its weight with that of the water contained therein governs the pressure rheostat 27, which rheostat is located in the circuit of the field of the pump motor 7; 28 is a limit switch which operates to secure the stoppage of the sand feeding motor 12 when the operation of the pump 3 stops; 29 is a starter for the motor 7 governed from the push button switch box 30; and 31 is a manually operated rheostat in the circuit of the field of the motor 7.

The operation of the pump 3 which pumps the mixture of abrasive and water up into the tank 1 from the sump 2 is controlled by the overflow through the pipe 25. This pipe leads into the receptacle 26 having an outlet 32 at its lower end. The relative amount of water flowing into the receptacle through the pipe 25 and out of the receptacle through the pipe 32 governs the quantity of water which is retained by the receptacle and therefore its weight. This receptacle is pivotally supported on a lever 33 fulcrumed upon a suitable bracket 34 as indicated at 35 and provided with a counter weight 36. Intermediate its ends at 37, the lever bears upon the plunger of the pressure or compression rheostat 27. This type of rheostat is well known in the art and consists of a series of carbon discs to which pressure is applied so that the conductivity of the resistance element made up of the series of discs decreases as the pressure increases. This resistance element is located in the circuit 38, which is in series with the field of the motor 7 which operates the pump 3. As the speed of operation of the pump increases, or the amount of liquid withdrawn through the pipes 4, 5, 6, etc. decreases, the overflow of the tank will increase, thus tending to raise the level of the liquid in the receptacle 26. This increases the pressure on the rheostat 27, so that the flow of current through the motor field is increased and the speed of the motor correspondingly decreased. The reverse occurs when the overflow is reduced, in which case the level in the receptacle 26 is lowered, the conductivity of the rheostat is reduced and the motor speeds up. The motor is in this way automatically controlled so that the upward velocity of the abrasive and water through the tank 1 is maintained constant, thus insuring that the fineness of the abrasive at any particular level is maintained constant. The pipe 25 is preferably closed at its lower end as indicated in Fig. 1^a and provided with the perforations 25^a so that the inertia of the water flowing down through the pipe is not applied to the receptacle 26 so that the operation of the device is not subject to disturbance incident to this factor. A uniform grinding effect is thus secured by each of the machines fed from one of the pipes 4, 5, 6, etc. The receptacle

is guided and maintained in a true vertical plane by use of an additional lever 39 pivoted at one end to the bracket 34 and at its other end to the receptacle. By proportioning the parts of the lever arm 33 so that the arm to the left of the fulcrum 35 is relatively short as compared with the other arm, the device is made very responsive to changes of weight in the receptacle 36, so that the regulation secured is sensitive and accurate. This also applies to the lever 42, later referred to which operates the rheostat 20.

A device operating upon a similar principle and including a pressure rheostat is also employed to automatically control the density of the mixture in the tank 1 so that the proportion of water to sand is maintained constant. In this device a vertical tube 19 is employed, open at both ends, and having the enlargement 40 at its upper end. This tube is pivoted for vertical movement upon the bracket 41 by means of the lever 42 and the link 43, and the lever 42 bears at 44 upon the plunger of the pressure rheostat 20 similar in construction to the rheostat heretofore described. This rheostat lies in the circuit of the field of the motor 12, such circuit including the connections 45 and 46. As the density of the mixture in the tank 1 increases, the distance which the column of water is forced up in the enlargement 40 above the level of the liquid in the tank increases, thus applying the pressure to the rheostat and decreasing the speed of rotation of the motor 12 so that the quantity of sand fed by the worm 11 is reduced. The reverse occurs when the density of the mixture decreases and the level of the liquid in the enlargement 40 moves down, as in such case the pressure on the rheostat is reduced, thus increasing the resistance in the motor field circuit and causing the motor to speed up. The liquid in the tube 19 and its extension 40 rises above the level of that in the tank since the tube contains clear water which is less dense than the mixture surrounding the lower end of the tube. Any abrasive which enters the lower end of the tube immediately settles out so that the density of the liquid is less in the tube than outside of the tube and the height of the column of liquid supported correspondingly greater. The density of the mixture in the tank is in this manner controlled and maintained constant. The tube 19 with its enlargement 40 is so arranged that the lower end 40^a of such enlargement is always in the liquid of the tank, so that in all its positions it is subject to substantially the same buoyant reaction, and as a result there is no abrupt departure from the uniform variation in weight depending upon the height of the column in the enlargement such as would be the case if, in the operation of the

apparatus, the level of the liquid in the tank fell below the bottom 40^a of the enlargement.

If, for any reason, the density in the tank is reduced beyond a predetermined point, a device is provided for ringing the bell 21 and calling attention to this condition. This device includes an electro-magnet winding 47 which swings the bar 48 to the left against the resistance of the spring 49 when the flow through the winding is increased beyond a certain point. This movement causes the bar to contact with the screw 50 so that a circuit through the bell 21 is completed from the battery 51 and the bell is rung. On the other hand, when the density of the mixture is increased beyond a certain point, the flow through the circuit 45, 46 is increased, thus reducing the flow through the shunt coil 47, so that the spring 49 moves the bar 48 into contact with the screw 52, thus providing a circuit through the bell 22 which rings, thus calling attention to the existing condition.

Provision is also made for automatically stopping the motor 12 in case the density of the mixture in the tank becomes too great. This device comprises the swinging bar 53 which is operated by the coil 54 which is arranged in shunt with respect to the field circuit. When the density of the liquid increases beyond a certain point and the resistance in the field circuit is correspondingly reduced, less current passes through the coil 54 and the spring 55 moves the bar 53 to the right so that the spring contact arm 56 moves away from the arm 57, thus breaking the circuit through the wires 57', 58 which lead to the operating coil of the motor starter 14. As soon as this circuit is broken, the spring in the motor starter opens the switch, thus stopping the motor. In order to start the motor after it has once been stopped, it is necessary to press in the starting push button 15.

An arrangement is also provided operating in conjunction with the mechanism just described for breaking the circuit through the wires 57', 58 and stopping the sand feed motor 12 when the pump 3 is, for any reason, stopped, or if the supply of liquid to or from the pump should be interrupted. This device comprises the limit switch 28 which lies in the circuit 57', 58. This switch is provided with an arm 59 carrying a roller which engages the end of the lever 33. When the receptacle 26 becomes emptied or nearly emptied, the counterweight on the lever 33 carries the left hand end thereof downward below the roller on the switch lever 59 so that such lever swings upward under the influence of a spring and breaks the circuit through the wires 57', 58, thus breaking the motor circuit in the starter 14,

as heretofore described, and causing the stop- 65 page of the motor 12.

In order to level up the top of the tank, a ring 60 is provided connected to a flange on the top of the tank by means of the flexible member 61, of rubber or other waterproof 70 material and this ring is itself leveled up by means of the bolts 62 extending through the top 63 of the tank. In this manner, the upper edge of the angle 60 may readily brought to a true vertical plane throughout the circumference of the tank. It is desirable to have the overflow around the entire perimeter of the tank as this secures a maximum discharge of the liquid in the tank to the pipe 25 per unit of time, as the level in the 80 tank rises, so that the control by the receptacle 26 acting through the rheostat is very rapid. The adjustment of the operation of the pump is, therefore, sensitive and accurate. 85

In order to maintain the level of the sump constant, a float 64 is employed (Fig. 3) which is connected to the bracket 65 by means of the lever 66 and link 67, the lever being secured at its other end to the gate 90 valve 68. This gate valve controls the supply of water through the water main 69 so that from time to time, as the level of the sump is reduced, due to the fact that not all of the water used in the grinding operation 95 is recovered, the valve is opened and an additional supply of water flows into the sump. In case the operation of the pump is discontinued, the mixture in the tank is prevented from flowing back into the sump 100 by means of the ball check valve 70 located in the lower end of the tank as indicated in Fig. 1.

Figs. 4, 5, and 6 illustrate a modification in so far as the method of supplying the sand to the sump is concerned. The grader itself, the pump and the means for controlling the operation of the pump by the overflow from the grader are the same as in the construction heretofore described and the same numerals are used in connection with both sets of apparatus. The member 40, whose position is regulated by the density of the mixture in the tank, and the pressure rheostat 105 20 operated thereby, are also the same as in the construction of Figs. 1, 2 and 3. In the present apparatus, the sand bin 71 may be located outside of the building so that it can be readily supplied by means of an overhead crane or telfer, and the motor 72, which runs 110 constantly, operates a valve 73 at the lower end of the sand bin or hopper instead of operating a screw feed as in the construction 115 of Fig. 1. The wear upon a feed of this kind is considerably less than is the case 120 with a screw feed such as that of Fig. 1. The sand is conducted from the bin to the 125 sump 2 by means of a chute 74 and prelimi-

nary to the deposit of the sand in the sump, it is screened by means of the rotary screen 75. This screen is rotated by means of the belt 76 driven from the countershaft 77, and the countershaft 77 is in turn driven by means of the belt 78 from the shaft 79, the latter shaft being driven by means of the belt 80 leading to the motor 72. A chute 81, open at the top, extends into the screen and catches any gravel or the like, which collects therein, and which is carried by the movement of the screen to a point where it can drop into the top of the chute from which it is removed or conducted away.

15 The valve 73 is mounted upon a shaft 82 and in opening is rotated in a clockwise direction as indicated by the arrow. The shaft 82 is provided with a depending arm 83 to which is secured the winding or coil 84 and this arm is swung to open the valve, when the winding is energized, by means of the arm 85 mounted loosely on the shaft 82, and provided with an armature 86 (Fig. 5) extending across the rear end of the magnet. The arm 85 is oscillated continuously back and forth, but is effective to swing the arm 83 keyed to the shaft 82 and open the valve, only when the winding is energized, so that the two arms 85 and 83 are connected together. The arm 85 is oscillated by means of the connecting rod 87 mounted upon a crank 88 carried by the shaft 79. The rod passes through a block 89 adjustable longitudinally of the arm 85 and provided with the pairs of nuts 90 and 91 for adjusting the tension upon the spring 92, by means of which a yielding connection is provided between the rod 87 and the arm 85. The valve shaft 82 also has keyed to it a third arm 93 for operating the water valve 94 which controls the flow of water from the pipes 95 to the lower end of the sand bin. A spring 96 normally presses the arm upward to close the valve. When the arms 85 and 83 are magnetically connected together as heretofore described, to secure an operation of the valve 73, a corresponding operation of the water valve 94 is secured, so that the water is admitted to the lower end of the sand bin to assist in feeding the sand out whenever the valve is opened.

50 The energizing of the magnet winding 84 to secure a feed of sand to the chute 74 is controlled by the pressure rheostat 20. This rheostat lies in a shunt circuit 97, 98, connected with the main lines 99 and 100 supplied with current from a suitable source. Also in shunt with the main lines 99 and 100 is the circuit 101, 102, leading through the magnet winding 103. The winding controls the armature bar 104 normally held in open position by means of the spring 105. The two contacts 106 and 107 which are connected when the bar 104 moves to the left 55 are connected to a circuit including the wires

108, 109 and 110 in which the winding 84 for controlling the valve 73 lies. If the density of the mixture in the grader rises above a predetermined point, the carbon discs in the pressure rheostat are forced together, thus decreasing the resistance so that more current passes through the circuit 97, 98 and correspondingly less current passes through the circuit including the magnet winding 103, so that the armature bar 104 moves to the right breaking the contact at 106 and 107 so that the current through the winding 84 is discontinued. This disconnects the arms 85 and 83 so that the valve 73 is no longer oscillated and the feed of sand to the chute 74 is stopped. When the density of the mixture in the tank 1 is reduced, the reverse operation takes place, the flow of current through the winding 103 increasing so that the armature bar 85 closes the contacts 106 and 107 and the flow of current through the magnet winding 84 occurs, thus connecting the arms 85 and 83 so that the valve 73 is oscillated back and forth permitting a flow of sand to the chute 90 and at the same time the water valve 94 is periodically opened causing a flow of water into the sand bin to loosen the sand. If the sand is frozen, warm water may be used to facilitate the feed.

95 The sand feeding arrangement is connected to the apparatus for controlling the speed of the pump 3 by an arrangement similar to that described in connection with Fig. 1. In the present construction the limit switch 28 lies in the circuit 109, 110, in which the winding 84 lies so that if the pump should stop and the lever 33 drop beyond a predetermined point, the lever arm 59 is operated to break the circuit 109, 110 and cause the movement of the sand valve 73 to stop, the result being the same as referred to heretofore in connection with the first type of construction.

100 In order to indicate the status of the sand feed, means are provided for showing whether the density is too great or too little by means of the colored lights 111 and 112. In order to accomplish this result, the magnetic winding 113 for operating the armature bar 114 is employed, such winding lying in the circuit including the wires 115 and 116. When the density of the mixture in the tank 105 rises above a predetermined point and the flow of current through the circuit, including the rheostat 20 and the wires 97 and 98, is increased, the flow through the winding 113 is correspondingly decreased and the spring 116 moves the armature bar 114 so that it connects the contacts 117 and 118 and causes a flow of current through the filament of the lamp 112, so that a red light 110 is secured at this point. When the density decreases, a reverse result is secured, an increased flow through the winding 113 being 115 120 125 130

secured so that the armature bar swings to the left connecting the contacts 119 and 120 and securing a flow of current through the filament of the lamp 111 which is provided with a green glass. In this manner, the density of the mixture is made visibly apparent to the operator, and the use of lights instead of bells as illustrated in the first type of construction is preferred as the lights indicate conditions even from a considerable distance, while this is not the case with the bells, and furthermore, the noise of the bells is more or less objectionable.

What I claim is:

1. In combination, apparatus for supplying abrasive to grinding mechanism comprising a grading tank arranged to discharge simultaneously to said mechanism from different levels in the tank, a pump for supplying a mixture of abrasive and water to the lower portion of the tank to provide a grading flow upward therethrough, and feed means controlled by the density of the mixture in the tank for supplying abrasive to said pump, said means including an upright tube in the tank, open at its lower end and having an enlargement at its upper end extending above the level of the water in the tank.

2. In combination, apparatus for supplying abrasive to grinding mechanism comprising a grading tank arranged to discharge simultaneously to said mechanism from different levels in the tank, a pump for supplying a mixture of abrasive and water to the lower portion of the tank to provide a grading flow upward therethrough, and feed means controlled by the density of the mixture in the tank for supplying abrasive to said pump, said means including an upright tube in the tank, open at its lower end and having an enlargement at its upper end extending above the level of the water in the tank and with its lower end adjacent such level.

3. In combination, apparatus for supplying abrasive to grinding mechanism comprising a grading tank arranged to discharge simultaneously to said mechanism from different levels in the tank, means for supplying a mixture of abrasive and water to the lower portion of the tank to provide a grading flow upward therethrough, abrasive feeding means including an electric motor for supplying fresh abrasive to said mixture, and means governed by the density of the mixture in the tank for controlling said feeding means, said means including a hydrometer in the tank and a rheostat operated thereby.

4. In combination, apparatus for supplying abrasive to grinding mechanism comprising a grading tank arranged to discharge simultaneously to said mechanism from different levels in the tank, means for

supplying a mixture of abrasive and water to the lower portion of the tank to provide a grading flow upward therethrough, abrasive feeding means including an electric motor for supplying fresh abrasive to said mixture, and means governed by the density of the mixture in the tank for controlling said feeding means, said means including a hydrometer in the tank and a pressure rheostat operated thereby.

5. In combination, apparatus for supplying abrasive to grinding mechanism comprising a grading tank arranged to discharge simultaneously to said mechanism from different levels in the tank, means for supplying a mixture of abrasive and water to the lower portion of the tank to provide a grading flow upward therethrough, abrasive feeding means including an electric motor for supplying fresh abrasive to said mixture, and means governed by the density of the mixture in the tank for controlling said feeding means, said means including an upright tube in the tank, open at its ends and having an enlargement at its upper end extending above the level of the water, and a pressure rheostat operated thereby.

6. In combination, apparatus for supplying abrasive to grinding mechanism comprising a grading tank arranged to discharge simultaneously to said mechanism from different levels in the tank, means for supplying a mixture of abrasive and water to the lower portion of the tank to provide a grading flow upward therethrough, abrasive feeding means including an electric motor for supplying fresh abrasive to said mixture, and means governed by the density of the mixture in the tank for controlling said feeding means, said means including an upright tube in the tank, open at its ends and having an enlargement at its upper end extending above the level of the water, an abrasive control valve, and a pressure rheostat operated by the tube and controlling said valve.

7. In combination, apparatus for supplying abrasive to grinding mechanism comprising a grading tank arranged to discharge simultaneously to said mechanism from different levels therein, means for supplying a mixture of abrasive and water to the tank to provide a grading flow therethrough, a container for abrasive, an outlet valve, a continuously operating motor for opening and closing the valve, a releasable connection between the valve and motor, an operating member positioned in the tank and governed as to the pressure which it exerts downwardly by the density of the mixture, and means governed by said member whereby said connection is made and broken as the density of the mixture varies.

8. In combination, apparatus for supplying abrasive to grinding mechanism com-

6
prising a grading tank arranged to discharge simultaneously to said mechanism from different levels therein, means for supplying a mixture of abrasive and water to the tank to provide a grading flow therethrough, a container for abrasive, an outlet valve, a continuously operating motor for opening and closing the valve, an electro-magnetic connection between the valve and motor, an operating circuit for said connection, an operating member positioned in the tank and governed as to the pressure which it exerts downwardly by the density of the mixture, and means governed by said member whereby said operating circuit is completed and broken as the density of the mixture varies.

9. In combination, apparatus for supplying abrasive to grinding mechanism comprising a grading tank arranged to discharge simultaneously to said mechanism from different levels therein, means for supplying a mixture of abrasive and water to the tank to provide a grading flow therethrough, a container for abrasive, an outlet valve, a continuously operating motor for opening and closing the valve, a releasable connection between the valve and motor, an operating member positioned in the tank and governed as to the pressure which it exerts downwardly by the density of the mixture, including an electric circuit and a pressure rheostat whereby said operating circuit is completed and broken as the density of the mixture varies.

10. In combination, apparatus for supplying abrasive to grinding mechanism comprising a grading tank arranged to discharge simultaneously to said mechanism from different levels therein, means for supplying a mixture of abrasive and water to the tank to provide a grading flow therethrough, a container for abrasive, an outlet valve from the container, a water inlet connection to the container provided with a valve, a continuously operating motor for opening and closing said valves, a releasable connection between the valves and the motor, an operating member in the tank and governed as to the pressure which it exerts downwardly by the density of the mixture, and means governed by said connection whereby said connection is made and broken as the density of the mixture varies.

11. In combination, apparatus for supplying abrasive to grinding mechanism comprising a grading tank arranged to discharge from different levels thereof to different units of said mechanism simultaneously, a pump for supplying a mixture of abrasive and water to the lower portion of the tank to provide a grading flow upward therethrough, a motor for the pump and means governed by the overflow from the tank for regulating the operation of said

70
pump, said means comprising a receptacle to which the overflow discharges provided with an outlet, and a pressure rheostat governed by the weight of the water in the receptacle.

12. In combination, apparatus for supplying abrasive to grinding mechanism comprising a grading tank arranged to discharge from different units of said mechanism simultaneously, a pump for supplying a mixture of abrasive and water to the lower portion of the tank to provide a grading flow upward therethrough, a motor for the pump and means governed by the overflow from the tank for regulating the operation of said pump, said means comprising a receptacle to which the overflow discharges provided with an outlet, and a pressure rheostat in the field of the motor governed by the weight of the water in the receptacle and controlling said motor starter.

13. In combination, apparatus for supplying abrasive to grinding mechanism comprising a grading tank arranged to discharge simultaneously to said mechanism from different levels in the tank, means for supplying a mixture of abrasive and water to the lower portion of the tank to provide a grading flow upward therethrough, an abrasive container, abrasive feeding means including a feed valve for the container, an electric motor for operating said valve, and a releasable connection between the motor and valve, and means governed by the density of the mixture in the tank for making and breaking said connection between the motor and valve, said means including a hydrometer in the tank and a pressure rheostat operated thereby.

105
14. In combination, apparatus for supplying abrasive to grinding mechanism comprising a grading tank arranged to discharge simultaneously to said mechanism from different levels in the tank, means for supplying a mixture of abrasive and water to the lower portion of the tank to provide a grading flow upward therethrough, an abrasive container, abrasive feeding means including a feed valve for the container, an electric motor operating said valve, and a releasable electric magnetic connection between the motor and valve, and means governed by the density of the mixture in the tank for controlling said connection, said means including an upright tube in the tank, open at its ends and having an enlargement at its upper portion, and a pressure rheostat.

to the lower portion of the tank to provide a grading flow upward therethrough, abrasive feeding means including an electric motor for supplying fresh abrasive to said mixture, and means governed by the density of the mixture in the tank for controlling said feeding means, said means including an upright tube in the tank, open at its ends and having an 5 enlargement at its upper portion, a motor starter, and a pressure rheostat operated by the tube and lying in the circuit of the field of the electric motor for controlling the speed of the motor and also arranged to stop the motor.

16. In combination, apparatus for supplying abrasive to grinding mechanism comprising a grading tank arranged to discharge from different levels thereof to different units of said mechanism simultaneously, a pump for supplying a mixture of abrasive and water to the lower portion of the tank to provide a grading flow upward therethrough, a motor for the pump and means 20 governed by the overflow from the tank for regulating the operation of said pump, said means comprising a receptacle to which the overflow discharges provided with an outlet, and a pressure rheostat governed by the 25 weight of the water in the receptacle, and lying in the circuit of the field of the motor.

17. In combination, apparatus for supplying abrasive to grinding mechanism comprising a grading tank arranged to discharge from different levels thereof to different units of said mechanism simultaneously, a pump for supplying a mixture of abrasive and water to the lower portion of the tank to provide a grading flow upward therethrough, a motor for the pump and means governed by the overflow from the tank for regulating the operation of said pump, said means comprising a receptacle 30 to which the overflow discharges provided with an outlet, a motor starter, and a pressure rheostat governed by the weight of the water in the receptacle and controlling said motor starter, said rheostat lying in the circuit of the field of the motor.

18. In combination, apparatus for supplying abrasive and water to grinding mechanism, comprising a grading tank for said abrasive and water arranged to discharge to said mechanism from different levels, an 40 abrasive container for supplying abrasive to said tank, means controlled by the density of the mixture in the tank for governing the supply of abrasive from said container to the tank, said means including an element in the tank which tends to vary with a change of level in the tank, means for producing in said tank an upward flow of the water relative to the abrasive so as to separate the abrasive into grades, and means responsive to variations in the ratio 45

of flow to discharge for automatically maintaining the said ratio substantially uniform.

19. In combination, apparatus for supplying abrasive and water to grinding mechanism, comprising a grading tank for 50 said abrasive and water arranged to discharge to said mechanism from different levels, an abrasive container for supplying abrasive to said tank, means controlled by the density of the mixture in the tank for governing the supply of abrasive from said container to the tank, means for producing in said tank an upward flow of the water relative to the abrasive so as to separate the abrasive into grades, means responsive to variations in the ratio of flow to discharge for automatically maintaining the said ratio uniform, and means governed by said ratio for entirely cutting off the supply of abrasive 55 when such rate of flow drops below a predetermined point.

20. In combination, apparatus for supplying abrasive and water to grinding mechanism, comprising a grading tank for 60 such abrasive and water arranged to discharge to said mechanism from different levels, means for producing in said tank an upward flow of the liquid relative to the abrasive so as to separate the abrasive into grades, receiving means extending around the tank 65 for receiving the overflow which passes over the upper peripheral edge of the tank, and means governed by the amount of overflow to said receiving means for controlling said rate of flow upward through the tank.

21. In combination, apparatus for supplying abrasive and water to grinding mechanism, comprising a grading tank for 70 said abrasive and water arranged to discharge to said mechanism from different levels, means for producing in said tank an upward flow of the liquid relative to the abrasive so as to separate the abrasive into grades, receiving means extending around the tank 75 for receiving the overflow which passes over the upper peripheral edge of the tank, means for leveling up said upper edge of the tank so that the overflow passing over such edge is substantially uniform along 80 the length thereof, and means governed by the amount of overflow to said receiving means for controlling said rate of flow upward through the tank.

22. In combination, apparatus for supplying abrasive and water to grinding mechanism, comprising a grading tank for 85 said abrasive and water arranged to discharge to said mechanism from different levels, and having an upper edge portion connected to the body portion by flexible means so that such edge may be adjusted to level it up, means for producing in said tank an upward flow of the liquid relative to the abrasive to separate the abrasive into grades, receiving means extending around the tank 90

in position to receive the overflow passing said upper edge portion, and means governed by the amount of overflow to said receiving means for controlling said rate of flow upward through the tank.

23. In combination, apparatus for supplying abrasive and water to grinding mechanism, comprising a grading tank for said abrasive and water arranged to discharge to said mechanism from different levels, an abrasive container for supplying abrasive to said tank, motor driven means for insuring a feed of abrasive from said container to the tank, a regulating device in the tank actuated by the density of the liquid, a rheostat operated thereby, and means governed by the rheostat for controlling said motor driven means.

24. In combination, apparatus for supplying abrasive and water to grinding mechanism, comprising a container for abrasive and water for supplying the mixture to said mechanism, and feed means controlled by the density of the mixture in the container for supplying abrasive thereto, said means including an upright tube in the tank open at its lower end extending above the level of the mixture in the container.

25. In combination, apparatus for supplying abrasive to grinding mechanism, comprising a container arranged to discharge to said mechanism, a container for abrasive, an outlet valve, a continuously operating motor for opening and closing the valve, a releasable connection between the valve and motor, an operating member positioned in the tank and governed as to the pressure which it exerts by the density of the mixture, and electrical control means governed by said member whereby said connection is made and broken depending upon said density.

26. In combination, apparatus for supplying abrasive to grinding mechanism, comprising a container arranged to discharge to said mechanism, a container for abrasive, an outlet valve, a continuously operating motor for opening and closing the valve, a releasable connection between the valve and motor, an operating member positioned in

the tank and governed as to the pressure which it exerts by the density of the mixture, and electrical control means including a pressure rheostat controlled by said member whereby said connection is made and broken depending upon said density.

27. In combination, apparatus for supplying abrasive to grinding mechanism, comprising a container arranged to discharge to said mechanism, a container for abrasive, an outlet valve, a continuously operating motor for opening and closing the valve, a releasable electro-magnetic connection between the valve and motor, an operating member positioned in the tank and governed as to the pressure which it exerts by the density of the mixture, and electrical control means governed by said member whereby said connection is made and broken depending upon said density.

28. In combination, apparatus for supplying a mixture of abrasive and water to grinding mechanism comprising a container for said mixture adapted to discharge to said mechanism, an abrasive container for supplying abrasive to said first container, motor driven means for securing a feed of abrasive from said abrasive container to said first container, a regulating device in said first container actuated by the density of said mixture, a rheostat operated thereby, and means governed by the rheostat for controlling said motor driven means.

29. In combination, apparatus for supplying a mixture of abrasive and water to grinding mechanism comprising a container for said mixture adapted to discharge to said mechanism, an abrasive container for supplying abrasive to said first container, motor driven means for securing a feed of abrasive from said abrasive container to said first container, a regulating device in said first container actuated by the density of said mixture, a pressure rheostat and a switch governed by the rheostat for controlling said motor driven means.

In testimony whereof, I have hereunto subscribed my name this 18th day of Jan., 1924.

HALBERT K. HITCHCOCK.
